UNITED STATES PATENT OFFICE.

EDWARD B. COLBY, OF BROOKLYN, NEW YORK.

STOVE.

SPECIFICATION forming part of Letters Patent No. 449,929, dated April 7, 1891.

Application filed February 21, 1890. Serial No. 341,300. (No model.)

To all whom it may concern:

Be it known that I, EDWARD B. COLBY, a citizen of the United States, residing at Brooklyn, in the county of Kings and State of New York, have invented certain new and useful Improvements in Stoves; and I do hereby declare the following to be a full, clear, and exact description of the invention, such as will enable others skilled in the art to which it applies to make and use the same.

This invention relates, generally, to stoves, and particularly to that class of heating-stoves known as "cylinder" or "sheet-metal" stoves; and it has for its object to provide a simple, durable, and cleanly stove having a grate in two parts, both of which may be oscillated in a horizontal plane at the same time and by the same means, and one of which may be dumped or tipped over without moving the other, and in providing a rest for said grates which may or may not form an integral part of the base of the stove; and it consists of the parts and combinations of parts hereinafter described and claimed.

In the accompanying drawings, forming a part of this specification, Figure 1 is a plan view of the grate and base of my improved stove; Fig. 2, a vertical section of the same on the line *x x*, Fig. 1; Fig. 3, a perspective view of the grate removed from the stove; Fig. 4, a plan view of the bottom of the grate-supporting ring; Fig. 5, a plan view of the top of the base proper; and Figs. 6 and 7 detail sectional views taken, respectively, on the lines *y y* and *x x*, Fig. 1.

Similar letters refer to similar parts throughout the several views.

A represents the cast-metal base of a stove, to which the sheet-metal body of the stove is to be secured. The base may be cast in one piece having a vertical annular projection *a* formed at its top and extending entirely round said base, with the exception of a short space immediately at the front thereof, with a suitable number of perforated lugs or ears *b* projecting therefrom at equal distances apart. The lower part of the sheet-metal body of the stove surrounds the annular projection *a* and is secured thereto by rivets or screw-bolts and nuts, as is customary, said rivets or screw-bolts passing through the sheet-metal body and through the perforated

ears or lugs *b*. From the inner side of the annular projection *a*, at the base thereof, a narrow shelf or ledge *c* projects at right angles entirely round the base, and from the edge of this shelf or ledge a narrow annular flange *d* extends downward, on the lower edge of which the ears or lugs *e* are cast, and from which they extend at right angles at suitable distances apart to form a firm support for and to permit of the free movement thereon in a horizontal plane of the grate-sections when the same are shaken. The ears or lugs *e* are cast of a length sufficient to afford a bearing for the grate-sections to the full extent of their oscillation, which is limited by the length of the slot *f*, formed in the side of the base. Outside of and surrounding the annular projection *a*, I form in the upper surface of the base a groove or duct *g*, the purpose of which is to catch the dust and finer ashes which sift or work their way between the inner face of the sheet-metal body and the outer face of the vertical annular projection *a*, and thus prevent the dust and ashes reaching the floor of the apartment containing the stove. By this simple means I obviate the annoyance occasioned by escape of the dust and ashes onto the floor and carpets, and am enabled to form the body and base separately, and provide a simple, durable, and inexpensive connection between the two and practically securing the same advantage as a dust-tight connection would afford were such practicable in this class of stoves.

The whole of the base just described is cast in one piece; but I may, if desired, and it may be preferred so to do, cast the base and the upper part thereof, which sustains the body, or to which body is directly secured, separately and secure them together by screw-bolts. In order to accomplish this, I cast the top of the base proper with a flat upper surface *h*, from the inner edge of which project at regular intervals the supporting-lugs *i*, having the V-shaped recesses therein, as shown clearly in Fig. 5. The upper part of the base, which may be termed a "ring" *k*, as shown in bottom plan view in Fig. 4, is formed with a dust groove or duct *g*, an upwardly-extending annular projection *a*, the inwardly-projecting shelf *c*, downwardly-projecting flange *d*, and supporting-ears or lugs *e*, similar to those de-

scribed in connection with the base, and in addition thereto I form or cast the lugs *l* (see Figs. 4 and 6) onto the rear surface of the flange *d*, which are adapted when the ring is placed 5 on the base to enter beneath the lugs or ears *i*, in order to lock the parts together and prevent the ring and the upper part or body of the stove from toppling over. These parts are also secured together by screw-bolts *m*, 10 (see Fig. 7,) passing through countersunk openings *n*, formed in the shelf *c* of the ring and entering the V-shaped recesses *j*, formed in the lugs *i*, where they are secured by nuts *o*. By this construction I am enabled to cast 15 the parts separately and then join them together in rigid manner at little expense, and rendering it possible at small expense to substitute a new part for a broken part should it become necessary.

20 The grate is composed of two sections, the outer of which, forming the side walls, consists of ring *p*, from the outer edge of which all around its circumference, except for a short space immediately at the front thereof, 25 where said ring is recessed, as at *p'*, project the horizontal short bars *q*, and from the center of the rear side of the ring extends a long bar *r*, and from each side near the front long bars *r'* are cast, as clearly shown in Figs. 1 30 and 3, and from the bottom or lower side of the ring *p* the bars *s* extend downward in an inclined direction to form a basket-shaped grate. At the rear side of the ring *p*, directly 35 opposite the recess or downwardly-extending offset *p'* formed therein, two bars *q'* are cast, which extend below the plane of the bars *s* and have cast on their lower ends the plates *s'*, on which rests one side of the inner or central 40 grate-section *B*, and also directly opposite each other at the sides of the ring *p*, I cast the depending lugs forming the hangers *t* *t'*, which project in a line parallel with the bars *s*, but extend below the plane of the same. The outer 45 grate-section, as thus constructed, leaves a clear but narrow space between the ends of its bars *q* and the inner face of the flange *d* of the base or ring *k*, through which ashes and small cinders may escape when the grate is shaken, and leaves also a central open bottom. It will 50 be observed that the bars *s*, forming what is termed herein the "walls" of the grate, are not joined or connected at their lower ends in any way, but project from the ring *p*, similar to teeth. For the central opening or bottom of the 55 outer grate-section I provide a grate-section *B*, which is formed of a ring *C*, having cast therewith the radial bars *D*, which extend from the outer circumference of the ring and are unconnected at their outer ends, and the 60 bars *E* extending from the inner side of the ring also unconnected at their ends. The bars *D* are of such length as not to reach the bars *s*; but a narrow space is left between the ends of the same all round the bottom of the 65 grate, and said inner grate *B* is hung with its upper surface on a plane with the ends of the bars *s*. The handle *F*, by which the grate

is shaken, and which also supports one side of the inner grate-section, is cast with the inner grate-section and extends therefrom 70 through the guard-plate *G* and the slot *f* formed in the side of the base, said handle resting on the hanger *t* and prevented from being pushed outward by the stops *u* *u'*, the former impinging against the inner side of 75 the hanger *t* and the latter against the guard-plate, and serving to hold the same in place while the opposite side of the central grate-section is supported by the short trunnion *v* resting in the hanger *t'* at that side of the 80 outer grate, and being held in place by a stop *v'* formed thereon. The outer grate-section is supported from the base or ring through its bars *r* and *r'* resting on the lugs or ears *e*. The ends of these bars are adapted to fit accurately against the flange *d*, thereby preventing the grate from being moved out of alignment and precipitated into the ash-pan and insuring its true and easy movement while being shaken. The length of the slot 85 *f* in the base is such as to limit the movement of the grate in either direction to about one-half the length of the ears or lugs, so that the bars *r* and *r'* cannot be pushed off the ends of 90 said ears or lugs during the operation of shaking the grate. The handle *F* is moved in a horizontal direction back and forth in the slot *f* as is customary to shake the grate, said handle fitting snugly in the hanger *t* and the trunnion *v* resting in the hanger *t'*, so that 95 when the handle is moved it carries with it both grate-sections. By forming the bars of the grate-sections like teeth it renders it almost impossible for the ashes and cinders to 100 clog the grate-sections, as often occurs where the bars are formed in casting the grate by forming slots therein between the bars and having the ends of the bars, both outer and inner, connected.

The inner grate-section may be tipped or 110 dumped to empty the ashes and cinders by giving the handle *F* a half turn toward the front of the stove, thereby dumping the ashes at the most convenient point for removal.

The advantage of a grate having a tipping 115 or dumping center or inner grate-section and a non-dumping outer grate-section surrounding the same over the ordinary grate, the whole of which must be tipped or dumped to empty the stove of ashes, is that there is no 120 liability in shaking the grate-sections to tip them over, as one of them, as far as any liability to tipping over is concerned, is practically rigid and immovable. Also by arranging the bars of the grate on the peripheries 125 of the rings they act as cleaners to knock or agitate the coals and cinders and thus facilitate the downward passage of the ashes. Both the upper and lower surfaces of the central grate-section are made flat or without 130 curve of any sort, thereby preventing the accumulation of hot ashes thereon, which are liable to warp the same.

Having thus described my invention, what

I claim as new, and desire to secure by Letters Patent, is—

1. In a grate, the combination, with the outer grate-section having the horizontal bars cast on its periphery and the inclined downwardly-projecting bars, of the center or inner grate-section having the horizontal bars cast on its periphery, the inwardly-projecting horizontal bars, and means for supporting said inner grate from the outer grate, substantially as described.

2. In a grate, the combination, with the outer grate-section having the short horizontal bars cast on its periphery, the long horizontal bars cast at suitable intervals on said periphery, the inclined downwardly-projecting bars, the hangers, and the supporting-plate, of the inner grate-section having the horizontal bars formed on its periphery, the inner bars, the trunnion, and the handle, substantially as described.

3. The combination, in a grate, of the outer non-dumpable grate-section having the horizontal bars projecting from its periphery, the inclined downwardly-projecting bars, the inner grate-section having the horizontal bars projecting from its periphery, the inner bars projecting toward the center of the sections, and means for connecting said sections, whereby the inner grate-section may be dumped, substantially as described.

4. The combination, in a stove, of the outer grate-section having the short horizontal bars projecting from its periphery, the horizontal bars arranged at intervals around said periphery and extending beyond the first-named bars, the downwardly and inwardly inclined bars cast with said grate-section, the base having the inwardly-projecting supporting-lugs cast therewith for said last-named horizontal bars, and the inner grate-section mounted or supported from the center of said outer grate-section, so that it may be dumped

independently of said outer section, substantially as described.

5. The combination, with the base of a stove having grate-supporting lugs, of a non-dumpable outer grate-section supported by said lugs, the hangers and the inwardly-projecting supporting-plate cast with said grate-section, the inner grate-section and the trunnion cast therewith and adapted to support said grate-section from said hangers, whereby both of said grate-sections may be given a horizontal movement and said inner section may be dumped in one direction, substantially as described.

6. The non-dumpable grate-section, consisting of the outer ring having the short horizontal bars projecting from its periphery, the long horizontal bars arranged at intervals round said periphery, the inclined downwardly-projecting bars, the hangers extending below the plane of said last-named bars, the inner grate-section supporting-plate, the inner grate-section having the horizontal bars projecting from its outer and inner faces, and the trunnion and handle cast with said inner grate, substantially as described.

7. The combination, in a stove, of the base having the flat upper surface, and the lugs or ears *i*, the ring *k*, having the groove or duct formed therein, the vertical annular projection, the horizontal shelf, the downwardly-projecting flange, the lugs or ears cast on the inner edge of said flange, the lugs cast on the outer face of said flange and adapted to enter beneath the lugs *i*, and screw-bolts for securing said ring and base together, substantially as described.

In testimony whereof I affix my signature in the presence of two witnesses.

EDWARD B. COLEY.
